Primary Examiner — Zenia I Bennett*(74) Attorney, Agent, or Firm* — Faegre Baker Daniels LLP**(57) CLAIM**

We claim the ornamental design for the connector for a flotation device, as shown and described.

DESCRIPTION

FIG. 1 is a perspective view of a connector for a flotation device of the present application configured to couple with a second connector of another flotation device; FIG. 2 is a side view of the connector of FIG. 1; FIG. 3 is another side view of the connector of FIG. 1; and FIG. 4 is a front view of the connector of FIG. 1; FIG. 5 is a rear view of the connector of FIG. 1; FIG. 6 is a top view of the connector of FIG. 1; and, FIG. 7 is a bottom view of the connector of FIG. 1. The broken lines in FIGS. 1-7 show the second connector and portions of the first connector which form no part of the claimed design.
